UNITED STATES PATENT OFFICE

110,936

DESIGN FOR A DENTAL APPLICATOR

Adolph D. Wiseman, San Francisco, Calif.

Application April 11, 1938, Serial No. 76,415

Term of patent 14 years

To all whom it may concern:

Be it known that I, Adolph D. Wiseman, a citizen of the United States, residing in the city and county of San Francisco, State of California, have invented a new, original, and ornamental Design for a Dental Applicator, of which the following is a specification, reference being had to the accompanying drawing, forming part thereof.

Fig. 1 is side elevational view of a dental applicator showing my new design and
Fig. 2 is a face view thereof.

I claim:

The ornamental design for a dental applicator, substantially as shown.

ADOLPH D. WISEMAN.
